UNITED STATES PATENT OFFICE.

JOHN M. SHAW, OF WATER VALLEY, MISSISSIPPI.

REVOLVING COTTON-PRESS.

SPECIFICATION forming part of Letters Patent No. 243,982, dated July 5, 1881.

Application filed April 9, 1881. (No model.)

To all whom it may concern:

Be it known that I, JOHN M. SHAW, a citizen of the United States, residing at Water Valley, in the county of Yalabusha and State of Mississippi, have invented Improvements in Revolving Cotton-Presses, of which the following is a specification.

The subject of my invention is a revolving cotton-press with two screws carrying pinions beneath the press bed or sill, which gear with a stationary cog-wheel of larger size, the screws having bearings also above the follower-block, in the upper part of the revolving frame. The follower-block is provided with open shoes or 10 clutches to fit over or engage with the screw-nuts, so as to facilitate the removing of said follower-block for filling the press. The follower-block also carries rollers working on 15 trackways of press-box. In the accompanying drawings, Figure 1 is a side elevation of my improved press, showing the follower-block elevated and press-box closed. Fig. 2 is a front elevation of the same, showing the follower-block up and the press-box 20 open and a bale ready for removal. Fig. 3 is a perspective view of the follower-block detached. Fig. 4 is a perspective view of the upper part of the press-box, showing the follower-block moved from over the top of the 25 press and the movable side-boards in position in readiness for filling in and tramping cotton.

A A are standards connected by a horizontal beam, A'. The press-screws are shown at B B, having bearings in the bed plate or sill 30 I, and having securely keyed on their lower ends cog-wheels C C, which gear with a stationary center wheel, D, of larger diameter, the proportions preferably being such as to give the screws from one and a half to two turns for 35 every turn of the press. The upper ends of the screws work in bearings j in the upper beams, J, of the revolving press-frame. The said frame consists of horizontal beams J J, connected by a transverse horizontal beam, H, and standards 40 K K, connected at their lower ends by sub-sills L L, on which the main sill or bed-plate I rests.

M represents an ink or pivot in the center of the stationary wheel D, supporting the bottom of the revolving press-frame.

N is a gudgeon secured to the top of the

press-frame, and turning in a suitable box in the upper stationary beam, A'.

E represents a follower-block, having firmly secured to its extremities clutch-shoes E', of 55 metal, which have lateral notches c' to receive and hold the flanged nuts F, and apply to the follower-block E the pressure derived from the rotation of the screws B B. The open slots in the clutch-shoes admit the ready removal of 60 the follower-block whenever it is not under pressure.

On the under side of the follower-block, at each end, are rollers O O, adapted to run on removable trackways P P, which are laid across 65 the top of the box, beneath the ends of the follower-block, when it is run up. The said follower-block is then moved bodily to one side to expose the top of the box for filling in and tramping the cotton. During this operation 70 detachable side-boards S S are placed in position, as shown in Fig. 4. When the press-box has been filled and tramped the side-boards S S are removed, the follower-block E is run back into its operative position over the press-box and engages with the nuts F, the trackways P P are withdrawn, and the press is then 75 again ready for operation.

The press-box Q and doors R may be of ordinary construction.

The ends T T of the press-box are held in by key-pieces U U, having beveled lower edges, so that when pressed down they force the said end-boards firmly home and hold them out of contact with the screws.

My press possesses several advantages over 85 any of the iron or wooden presses now in common use. It is speedy, and yet with an eight or ten foot lever a single mule can press a six hundred or seven hundred pound bale of cotton. It presses down evenly, making both ends 90 of the bale the same size. It does not require large timbers to build it, and is not dangerous, and its construction permits it to be placed close to the lint-room, so that it may readily 95 be covered over.

Having thus described my invention, the following is what I claim as new therein and desire to secure by Letters Patent:

1. The combination of the revolving press-box, the screws having bearings in the rotary frame both above and below the press-box, the

pinions keyed to the lower ends of the screws and gearing with a stationary central wheel, and the follower-block drawn down by the rotation of the screws imparted by the revolution of the press on its own axis, as herein shown and described.

2. The follower-block constructed with open clutch ends or shoes, in combination with flanged or grooved nuts, over which the said clutch ends may be slipped, as herein shown and described.

3. The combination of the detachable follower-block and the removable trackways on which the said block may be moved from over the press-box.

JOHN M. SHAW.

Witnesses:

JOHN C. HUDSPETH,
SAMUEL LEVITT.
